UNITED STATES PATENT OFFICE.

FRED A. NEIDER, OF AUGUSTA, KENTUCKY.

WROUGHT-METAL NUT.

No. 904,555.

Specification of Letters Patent. Patented Nov. 24, 1908.

Application filed October 30, 1907. Serial No. 399,886.

To all whom it may concern:

Be it known that I, FRED A. NEIDER, a citizen of the United States of America, and resident of Augusta, county of Bracken, 5 State of Kentucky, have invented certain new and useful Improvements in Wrought-Metal Nuts, of which the following is a specification.

The object of my invention is a wrought 10 metal nut which may be manufactured with a minimum amount of waste material.

Referring to the accompanying drawings, in which I have illustrated blanks and nuts embodying my invention, Figure 1 is a detail view of a strip of wrought metal from which the rolled tube is to be formed. Fig. 15 2 and Fig. 3 are detail views of different forms of rings to be used to surround the rolled tubes. Fig. 4 is a perspective view of 20 one form of rolled tube. Fig. 5 is a perspective view of a blank formed from a rolled tube and a ring. Fig. 6 is a central sectional view of the blank shown in Fig. 5. Fig. 7 is a central sectional view of a cap 25 nut. Fig. 8 is a perspective view of a modified form of blank formed from a tube and ring. Fig. 9 is a perspective view of a capped nut.

Referring to the parts: Tube, A, may be 30 rolled either to a form circular in cross section or to one whose section form is four cornered or hexagonal. After the tube is rolled, a ring, B, whose aperture corresponds

in shape to the section of the tube, is forced down over the tube, so as to stand a short 35 distance from one end of the tube. This forms the blanks shown in Figs. 5 and 8, which are commercial articles. Screw threads are then cut upon the interior of tubes, A. A cap, C, may then be placed 40 over the end of tube, A, and the edges of the cap may be curved under the periphery of the ring, B. A wrought metal nut is thus produced without the loss of material.

What I claim is:

1. A nut comprising a tube of sheet metal split from end to end, and having screw-threads upon its interior, and a ring fitting snugly around the tube.

2. A capped nut consisting of a split tube 50 having screw-threads upon its interior, a ring fitting snugly around the tube and a cap fitting over the end of the tube and having its edges bent under the periphery of the ring.

3. A capped nut consisting of a tube formed from a sheet of metal, a ring surrounding the tube, and a cap formed from a disk which contacts the end of the tube and has its edges bent over the periphery of the 60 ring.

FRED A. NEIDER.
